Attorney.

UNITED STATES PATENT OFFICE.

HARRY ELLWOOD SLOAN, OF PHILADELPHIA, PENNSYLVANIA.

TYPE-TURTLE OR FUDGE-BED FOR ROTARY PRINTING-PRESSES.

1,316,338.

Specification of Letters Patent. Patented Sept. 16, 1919.

Application filed January 18, 1919. Serial No. 271,877.

To all whom it may concern:

Be it known that I, HARRY ELLWOOD SLOAN, a citizen of the United States, residing at Philadelphia, in the county of Philadelphia and State of Pennsylvania, have invented a new and useful Type-Turtle or Fudge-Bed for Rotary Printing-Presses.

This invention relates to an improvement upon the type-turtle or fudge-bed shown and described in U. S. Letters Patent #1,134,340. Practical experience with the type-turtle or fudge-bed referred to has demonstrated the necessity of making certain changes to render the same commercially efficient, which is one object of the present invention. Another object is to reduce the number of parts and strengthen the construction thereof. A further object is to provide resiliently held, shiftable bolts equipped with self-aligning bits. With these and other objects in view the invention consists of the improvements hereinafter described and finally claimed.

The nature, characteristic features and scope of the invention will be more fully understood from the following description taken in connection with the accompanying drawings forming part hereof, and in which:

Figure 1, is a top or plan view of a type-turtle or fudge-bed embodying features of the invention.

Fig. 2, is a view of the same in longitudinal section, and

Fig. 3, is a view of the same in transverse section.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, 10 designates a bed-plate fixed to which as by screws 11 are end plates 12 and 13. 14 designates side plates and 15 designates a plurality of ribs removable with respect to the bed-plate and spaced apart to form grooves 15' for the reception of the webs or shanks of type-slugs 16. The end plate 12 is apertured for the passage there-

through of a plurality of endwise shiftable bolts comprising heads 17 of relatively large diameter and stems 18 of relatively small diameter. Between the heads 17 and the outer wall of the end plate 12 and coiled around each stem 18 is a spring 19 for normally pressing a bolt toward the grooves 15'. A shiftable head 20 normally in abutting position with the end plate 12 is present and the stem of heads 17 are fixed with respect to the shiftable head by means of nuts 21, said head being relatively thick and countersunk to accept said nuts. The heads 17 are slotted to accept horizontally disposed type-slugs 22 which, laterally considered, are relatively broad and are each provided with a knife-edge. These bits 22 are pivoted as at 23 with respect to a head 17 and the knife-edges thereof are notched as at 24 in order to escape contact with a rib 15, so that in effect each bit is provided with a pair of type-slug engaging portions. As clearly shown in Fig. 3 the heads 17 are disposed in staggered relation so that there is an upper and a lower row of heads. By this arrangement alternate grooves 15' are in alignment with the spaced knife-edges of the upper row of heads 17 and those grooves as bridged or spanned by the upper row of bits are in alignment with the knife-edges of the lower row of heads. In other words every groove has positioned in alignment therewith at least a portion of a bit. Because of the pivotal arrangement of a bit the same may be moved around its pivot point so that a bit may be adjusted to compensate for any inequality in a type-slug bit engaging surface. By moving the head 20 in a direction away from the end plate 12 the bits may be caused to be shifted away from the grooves 15' so that one or more lines of type-slugs may be removed from or positioned within the type-turtle. For convenience in shifting the head 20 I have designed a tool comprising a foot portion 25 terminating in a handle 26 secured to which are laterally extended journals adapted to engage sockets 27 fixed to the movable head 20. In practice the foot portion of the tool is inserted within the aperture 30 of the type-turtle base, through which is passed a bolt for clamping the type-turtle to a press cylinder, and the journals are fitted to the sockets 27 so that by moving the tool handle to the left in Fig. 2, the foot abutting

against the wall of said aperture, the head 20 may be moved away from the end plate 12. The end plate 13 is provided with upper and lower type-slug engaging members 29, 5 each comprising a continuous strip of metal provided with a knife-edge. These members are fixed to the end plate 13 by forcing the same within slots made for the purpose.

The following advantages may be claimed 10 for the present type-turtle over that disclosed in the aforesaid patent:—

By employing the enlarged heads with pivoted bits a greatly reduced number of shiftable members are employed. This reduces cost of manufacture, increases strength 15 of the end plate, permits of the use of a stem of reduced diameter and the use of a stronger coiled spring. By employing stems of reduced diameter nuts may be secured 20 to the stem ends instead of screws as formerly applied. These features in addition to the fact that the bits are self-aligning adds to the commercial value of the type-turtle. By making the movable head thicker break- 25 age thereof is reduced to a minimum. Heretofore this movable head was subject to continual breakage but could not be increased in size because the screws employed prohibited such increase. By employing a 30 thicker head and countersinking same to accept the nuts as in the present case this difficulty has been overcome. By the strips 29 in the end plate 13 the construction has been cheapened, strengthened and made more 35 efficient than by the use of pins as disclosed in the aforesaid patent.

It will now be apparent that I have devised a novel and useful construction which embodies the features of advantage enumerated 40 as desirable in the statement of the invention and the above description and while I have in the present instance shown and described the preferred embodiment thereof which has been found in practice to give 45 satisfactory and reliable results, it is to be understood that the same is susceptible of modification in various particulars without departing from the spirit or scope of the invention or sacrificing any of its advantages.

50 What I claim is:—

1. In a type-turtle or fudge-bed including complementary type-slug receiving grooves, end plates of which one is apertured for the passage therethrough of endwise-shiftable, 55 resiliently held members, type-slug engaging bits pivoted to said members at least a portion of a bit being aligned with a groove and means for moving said members away from said grooves.

60 2. In a type-turtle or fudge-bed including complementary type-slug receiving grooves, end plates of which one is apertured for the passage therethrough of endwise-shiftable, 65 resiliently held members, type-slug engaging bits having knife-edges pivoted to said

members at least a portion of the knife-edge of a bit being aligned with a groove and means for moving said members away from said grooves.

3. In a type-turtle or fudge-bed including 70 complementary type-slug receiving grooves, end plates of which one is apertured for the passage therethrough of endwise-shiftable, resiliently held members consisting of stems having slotted heads, type-slug engaging 75 bits having pivotal relation with said slotted heads at least a portion of a bit being in alignment with a groove and means for moving said members away from said grooves.

4. In a type-turtle or fudge-bed including 80 complementary type-slug receiving grooves, end plates of which one is provided with endwise-shiftable, resiliently held members, type-slug engaging bits pivoted to said members which bits are each provided with 85 a knife edge having a notched portion the unnotched portions of a bit being aligned with certain of said grooves and means for moving said members away from said grooves. 90

5. In a type-turtle or fudge-bed including complementary type-slug receiving grooves, end plates of which one is provided with endwise-shiftable, resiliently held members disposed laterally of the type-turtle or fudge-bed in staggered relation, type-slug 95 engaging bits pivoted to said members which bits are each provided with a knife-edge having a notched portion the unnotched portions of a bit being aligned with 100 certain of said grooves and means for moving said members away from said grooves.

6. In a type-turtle or fudge-bed including complementary type-slug receiving grooves, end plates of which one is provided with 105 fixed type-slug engaging means and of which the other is apertured for the passage therethrough of endwise-shiftable resiliently held members comprising stems having slotted heads pivoted to which are type-slug engaging bits, a shiftable head through which said stems extend said head having counter-sunk portions, nuts for the ends of said stems said nuts being accommodated by the said counter-sunk portions of 110 said head and means for shifting said head away from said end plate.

7. A type-turtle or fudge-bed constructed for type-slug reception, end plates of which one is provided with fixed type-slug engaging means and of which the other is provided with resiliently held, shiftable members extended across the entire width of the type-turtle or fudge-bed in staggered relation and type-slug engaging bits carried by 115 and movable laterally with respect to said members.

8. A type-turtle or fudge-bed constructed for type-slug reception, end plates of which one is provided with fixed type-slug engag- 120

130

ing means and of which the other is provided with resiliently held, shiftable members extended across the entire width of the type-turtle or fudge-bed in staggered relation and type-slug engaging bits having knife edges carried by said members and movable laterally with respect to said members.

9. In a type-turtle a plurality of resiliently held, shiftable members extended substantially across the entire width of the type-turtle and a type engaging bit carried

by each member and movable laterally with respect thereto.

10. In a type-turtle provided with type receiving grooves, shiftable members extended substantially across the entire width of the type-turtle and a type engaging bit carried by each member and movable laterally with respect thereto at least a portion of a bit being alined with a groove.

In testimony whereof, I have hereunto signed my name.

HARRY ELLWOOD SLOAN.
